UNITED STATES PATENT OFFICE.

FREDERICK C. JOHNSON, OF JERSEY SHORE, PENNSYLVANIA.

MACHINE FOR CUTTING HOLES IN METALLIC PANEL-BOXES, &c.

1,232,926.

Specification of Letters Patent. Patented July 10, 1917.

Application filed August 11, 1916. Serial No. 114,410.

To all whom it may concern:

Be it known that I, FREDERICK C. JOHNSON, a citizen of the United States, residing at Jersey Shore, in the county of Lycoming and State of Pennsylvania, have invented certain new and useful Improvements in Machines for Cutting Holes in Metallic Panel-Boxes, &c., of which the following is a specification.

10 As is well known, panel boxes used in connection with systems of electrical distribution are, for the most part, of steel and generally are furnished by the manufacturers without holes. When being adapted for use the holes are made in the particular locations determined by the specific arrangement of the connections and associated devices. The cutting of the holes has required considerable labor, and two men 20 using hand tools generally are necessary to effect the operation.

The main object of my invention is the provision of a suitable machine by which the holes can easily and quickly be made 25 and which machine can be operated by one person. However, it is not intended that the machine shall be restricted to this particular use, as it may be employed to cut holes in any metallic plates, or bars, or 30 the like, for any purpose desired.

With the above recited ends in view, my invention consists in certain novelties of construction and combinations of parts as herein set forth and claimed.

35 The accompanying drawings illustrate an example of the embodiment of the invention constructed and the parts combined according to the best method of procedure I have so far devised for the purpose.

40 Figure 1 is a side view in elevation of the entire machine, showing part of a metallic panel, through which a hole is to be cut, clamped in position.

Fig. 2 is a top plan view of Fig. 1 with 45 the panel removed.

Fig. 3 is a front end view in elevation.

Fig. 4 is a bottom plan view of the cutter block, showing the centering pin or point, cutter, and ratchet and pawl mechanism.

50 Fig. 5 is substantially a vertical sectional view of the cutter block and the parts associated therewith.

Fig. 6 is a detail view of the cutter.

Fig. 7 is a perspective view of one of the retaining plates.

55

The frame of the machine consists of a clamp brace A, preferably of cast metal, having an arm B provided with a slot C, a parallel arm D widened to form a table or bed to receive a box panel or plate, for example, the panel E through which the holes are to be cut, two spaced threaded holes F F within which are two threaded clamping screws G G for holding the panel E upon the table, and a slot H to receive 60 the fingers of the hand for holding and carrying the machine.

The brace may have suitable strengthening ribs, as I. The central part of the table or bed should be in a plane below the 65 ends thereof, as shown, so the cutter will not engage the surface of the bed when the hole has been cut, and the slot C in the arm should be bounded by bearing surfaces J for a washer. Slot W of any de- 70 sired depth at the rear of the table is present to receive the flange of the panel.

The rotary cutter block K has a central opening L through which extends an adjusting screw bolt and centering pin M 75 having at the top end a nut and washer N O, and a nut P by which the screw bolt is adjustably and rigidly held in the slot C of the frame, and at the lower end a centering point Q about which the cutter 80 block rotates as a center.

The adjusting screw bolt is reduced in diameter at R within the cutter block and the surface of the reduced portion is engaged by a set-screw S, thus providing for 85 the raising or lowering of the cutter block relative to the screw bolt, the distance between the shoulders defining the said part R, as clearly shown by Fig. 5.

The numeral 1 designates a cylindrical 90 hole in the side of the block; 2, an open slot at the bottom of the hole; 3, the cutter of any approved type secured to or integral with a cylindrical head 4 having a threaded opening 5 therethrough, said head being located within the hole 1 and the cutter projecting below the slot; 6, a threaded 95 adjusting screw engaging the head 4 which supports the cutter; 7, a washer; 8, the head of the adjusting screw; 9, 9, two curved removable clamping plates cut away to en- 100 105

gage the shank of the screw at adjacent ends; and 10, 10, two screws for securing the plates to the cutter block.

The cutter block is provided with a series of ratchet teeth 11 about its circumference, and the top of the block fashioned with a bearing boss 12 and a ball bearing boss 13, a plate 14 with a ball bearing surface 15 being removably secured to the boss 12 by screws, as shown. Balls 16 are located between the bearings and project above the surface of the plate. A threaded nut 17 on the adjusting screw rod frictionally engages the balls. About the boss 12 and below the plate 14 is located one end 15 of an operating lever 18 which has pivoted to its under surface a pawl 19 yieldably held in engagement with the ratchet teeth by a spring 20 bearing against a pin 21 secured to the lever arm.

The method of using the machine is obvious from the foregoing description. As shown by Fig. 1, the steel panel or other plate is firmly clamped upon the table or bed, the cutter block properly supported from the slotted arm through the medium of the clamping nuts, the centering point brought in contact with the panel where the hole is to be cut, the cutter adjusted according to the diameter of the desired hole, the nut tightened upon the ball bearings, and the lever then reciprocated, rotating the cutter block and cutter.

The machine as described provides a means which can be operated by one person for quickly and easily cutting holes in panel boxes wherever desired, thus minimizing labor and saving time. As previously stated, the machine can be used for cutting holes in other plates or bars, and for special uses the size of the machine may be of relatively large dimensions. While I have illustrated and described only one embodiment of the invention, it is intended to embrace within the scope of the claims other embodiments embodying unsubstantial variations, changes, and modifications.

What I claim is:

1. The combination in a machine for cutting holes, of a clamp brace having an arm, an arm spaced therefrom forming a table or bed, means for clamping a panel or plate to the table, a rotary cutter block carrying a cutter, means for centering the cutter block, means for vertically adjusting the cutter block and cutter relative to the said means for centering the cutter block, means for rotatably supporting the cutter block between the said arms, and means for rotating the cutter block and cutter.

2. The combination in a machine for cutting holes, of a clamp brace having an arm, an arm spaced therefrom forming a table or bed, means for clamping a panel or plate to the table, a cutter block carrying a cutter,

means for centering the cutter block, means for rotatably supporting the cutter block between the said arms, and means for rotating the cutter block and cutter; the means for supporting the cutter block consisting of an adjusting screw bolt carrying the means for centering the cutter block.

3. The combination in a machine for cutting holes, of a clamp brace having an arm, an arm spaced therefrom forming a table or bed, means for clamping a panel or plate to the table, a rotatable cutter block carrying an adjustable cutter and a ratchet and pawl mechanism, means for centering the cutter block, and means for adjustably supporting the cutter block with its attachments between the arm having the table or bed and the other arm.

4. The combination in a machine of the character described, of a U-shaped frame having substantially parallel arms spaced apart, one of said arms having a slot and the other arm a work supporting table or bed, of an adjusting screw bolt provided with nuts for clamping one end of the bolt within the said slot and the other end having a centering point, means for holding the material to be worked upon the table, and a cutter block mounted on the bolt and carrying a cutter and means for rotating the cutter block.

5. The combination in a machine of the character described, of a frame having parallel arms, one of said arms fashioned to form a work table or bed, clamping screws carried by the other arm, a rotary cutter block carrying an adjustable cutter and means for rotating the block, and centering means for the said block and upon which means the cutter block is adjustably mounted, said centering means supporting the block and its attachments from the arm parallel with the table.

6. A frame having two parallel arms one fashioned to form a work supporting table, and the other adapted to support a rotary cutter block, means for supporting the block from said arm and centering the block, a radially adjustable cutter carried by the block, and ratchet and pawl mechanism for rotating the block.

7. A frame having two parallel arms one fashioned to form a work supporting table, and the other adapted to support a rotary cutter block, a rotary cutter block, means for supporting the block from said arm and centering the block, an adjustable cutter carried by the block, means for shifting the cutter block and cutter relative to said supporting means, and ratchet and pawl mechanism for rotating the block.

8. The combination of a cutter block carrying an adjustable cutter and ratchet and pawl mechanism, a screw bolt with a centering point at one end and means for support-

ing the bolt at the other end from a frame, said bolt carrying the cutter block so the latter can be rotated thereupon, and means for adjusting the block lengthwise of the said bolt.

9. The combination of a cutter block carrying an adjustable cutter and ratchet and pawl mechanism, a screw bolt with a centering point at one end and means for supporting the bolt at the other end from a frame, said bolt carrying the cutter block so the latter can be rotated thereupon, means for adjusting the block relative to the bolt, and a threaded nut above the block on the rod and engaging the block.

10. The combination of a cutter block car-

rying an adjustable cutter and ratchet and pawl mechanism, a screw bolt with a centering point at one end and means for supporting the bolt at the other end from a frame, 20 said bolt carrying the cutter block so the latter can be rotated thereupon, means for adjusting the block relative to the bolt, and a nut on the rod above the block engaging balls supported by the block.

25

In testimony whereof I affix my signature in the presence of two witnesses.

FREDERICK C. JOHNSON.
